D. H. McCRAY

SPLICING NEEDLE AND TUCKER

Filed July 18, 1924

Patented June 9, 1925.

1,540,790

UNITED STATES PATENT OFFICE.

DAVID H. McCRAY, OF TULSA, OKLAHOMA.

SPLICING NEEDLE AND TUCKER.

Application filed July 18, 1924. Serial No. 726,763.

To all whom it may concern:

Be it known that I, DAVID H. McCRAY, a citizen of the United States, residing at Tulsa, in the county of Tulsa and State of Oklahoma, have invented certain new and useful Improvements in Splicing Needles and Tuckers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a splicing needle and tucker, particularly designed for making a splice in a wire cable. Wire cables such as are used in the oil well industry must be spliced from time to time and the splice must of necessity be neatly made without any loose ends which are liable to catch during the run period, so I have provided a novel means for making a neat or blind splice and the invention consists in certain novel parts and combinations of parts, all of which will be apparent by reference to the following description in connection with the accompanying drawings, in which

Fig. 1 is a perspective view of a cable showing the spliced ends with a needle or marlin spike with a core cutting blade.

Fig. 2 is a perspective view of the partially spliced cable showing the spliced needle or marlin spike and the tucker in position to complete the splice.

Fig. 3 is a cross sectional view through the tucker, the tucking needle being shown in edge view, and

Fig. 4 is a perspective view of one end of a cable.

When the cable 1 has its ends spliced together, the ends of the two strands 2 and 3 are loose so a needle or marlin spike 4 is inserted, the marlin spike or needle having an enlarged portion 5 near its end with a cutting edge which will cut the fibre core 6, then the tucker blade 7 is inserted through several of the strands as shown in Fig. 2. The helper then reaches in with a pair of pliers 8 or similar tool and grasps the core 6 so that it can be pulled out of the cable to make room for one of the strands for example 2 which may now be tucked in by a tucker bar comprising a lever 9 pivoted on

the sleeve 10 adjustably mounted on the tucker blade 7 and held in any adjusted position by the set screw 11. The pivot 12 secures the bar 9 to the sleeve 10.

One end of the tucker bar is provided with a handle 13. The other end has a half round groove 14 receiving the loose strand so that it can be pushed into the space previously occupied by the core 6. The cable is held from turning during this time by the marlin spike or needle 4, the bar 9 carries a chain or other flexible connection 15 to which is secured a stop pin 16 passing through an opening 17 in the blade 7 so that as the tucker bar exerts pressure against the strand 2, the cable will be held against longitudinal movement on the blade 7 by the stop pin 16.

When one strand is tucked in the operation is repeated for the other strand, therefore a neat effective blind or invisible splice is made with the free ends of the splice tucked in the center of the cable so that liability of their catching on any projection will be entirely eliminated. The marlin spike 4 and the tucker blade 7 is provided with T-heads 19 and 20 which become effective in hammering the cable into shape after the splice is completed. Of course it is understood that after a sufficient length of the core has been removed from the center of the cable, its extended end will be severed close to the cable and the end of the core tucked into the center of the cable so that it will be entirely enclosed between the cable strands.

What I claim and desire to secure by Letters-Patent is:—

1. Means for splicing a cable comprising a blade, a tucker rod adjustably mounted on the blade and a cable stop on the blade.

2. Means for splicing a cable comprising a blade, a tucker rod adjustably mounted on the blade and a cable stop on the blade, the cable stop being removably secured to the blade and means for permanently connecting the stop to the bar.

3. In a device of the class described, a cable engaging blade, a sleeve on said blade, means for binding the sleeve to the blade, a bar pivoted on the sleeve, a stop pin for engaging an opening in the blade and a flexible connection between the stop pin and the bar.

4. In a device of the class described, a blade, a sleeve on the blade, means for mak-

ing the sleeve fast to the blade, a tucker bar pivoted on the sleeve having a strand engaging groove at one end and a cable stop on the plate.

5. In a device of the class described comprising a blade having a hammer handle on one end and a perforation on the other, an

adjustable sleeve on the blade, a tucker bar pivoted on the sleeve, a pin for engaging the perforation and a flexible connection between the pin and the bar. 10

In testimony whereof I affix my signature.

DAVID H. McCRAY.
